UNITED STATES PATENT OFFICE.

EDDIE N. GOINS, OF MONONGAH, WEST VIRGINIA.

BRAKE MECHANISM FOR MINING CARS.

Application filed June 1, 1927. Serial No. 195,697.

The present invention relates to an improved brake mechanism especially adapted for mining cars and has for one of its important objects to provide a brake mechanism applicable to such cars in such a manner and constructed in such wise that the brake shoes of the brake bar may be applied to the wheels incident to the operation of a bumper structure thereby preventing the cars when in a train from crowding upon one another, particularly in going down an incline, and thereby doing away with a mine operator for each car.

Another important object of the invention aims to provide brake mechanism of this kind applicable to mining cars wherein the bumpers are employed to actuate the brakes to prevent the cars from crowding one another in descending an incline and to operate the same way on a level grade, particularly when a train of cars is being brought to a stop after travelling at a rapid rate of speed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a mining car embodying the features of my invention.

Figure 2 is a front elevation thereof partly in section,

Figure 3 is a rear elevation thereof,

Figure 4 is a top plan view thereof,

Figure 5 is a bottom plan view thereof,

Figure 6 is a detail vertical longitudinal section taken substantially on the line 6—6 of Figure 4,

Figure 7 is a sectional view taken substantially on the line 7—7 of Figure 4,

Figure 8 is a longitudinal vertical section taken substantially on the line 8—8 of Figure 4,

Figure 9 is a perspective view of one of the brake shoes,

Figure 10 is a perspective view of one of the brake shoes operating rods.

Referring to the drawing in detail it will be seen that the numeral 5 denotes the body of the mine car mounted on wheels 6 in the usual well known manner. The rear end of the body 5 has a tail gate 7 held in place by arms 8 pivoted at 9 and engageable in keepers

10 and having pin and slot connections 11 with a manipulating rod 12 so that the tail gate may be released for dumping purposes when desired. On each side of the body 5 there is rockably mounted an arm 14 and an arm 15 the former at the rear of the car and the latter at the front thereof. The latter arm 15 is pivoted intermediate its ends. Brake actuating rods 16 are connected with the upper ends of the arms 14 and 15 and extend toward each other and support brake shoes 17 by means 18 or in any other suitable manner. A bracket 19 projects outwardly from the center of each side of the body and then is curved upwardly and has fulcrumed on the upper end thereof a lever 20 with the opposite extremities of which are pivotally engaged the rods 16. These rods 16 see Fig. 10 have horizontal offset ends 21 for engaging the arms 14 and 15 and depending offset ends 22 for engaging the lever 20. Thus it will be seen that the shoes will move in opposite directions in unison so as to be applied to the front and rear wheels simultaneously and to be released therefrom simultaneously. A casing 24 is mounted at the front of the body 5 and has the shank 25 of a bumper 26 slidable therein and pressed outwardly normally by a plurality of springs 28 which are engaged in a cross piece 29 mounted on the front axle of the wheels 6 as is clearly illustrated in Figure 8. Lugs 30 project laterally from the shank 25 through slots 31 in the casing 24 and engage with the lower ends of the arms 15 as is clearly shown in Figure 1. Thus it will be seen that if the car abuts the car in front of the same the shank 25 is moved rearwardly in the housing or casing 24 against the tension of the springs 28 and will rock the arms 15 to apply the brake shoes 17 through the operation of the brake rods 16 and the levers 20.

A pair of pawls 33 are pivotally mounted in brackets 34 rising from the forward end of the casing 24 and engage in notches 35 to prevent the shank 25 from sliding inwardly of the casing 24. A pawl 36 has a hook end 37 shown clearly in Figure 8 and engages with a longitudinal series of ratchet teeth 39 on the shank 25 for preventing the outward movement of the shank when the same has once been pushed in. This pawl 36 is pivotally mounted on brackets 40 rising from the forward end of the casing 24. The pawls 33 are operable by a cable 42 in

order that they may be released while the pawl 36 is operable by a cable 43 in order that it may be released. These cables are trained through openings 44 and 45 respectively in the bottom of the body 5 and extend to the rear corners where they are detachably hooked as at 46. Each of the cables 42 and 43 have branches 47 and 48 respectively trained over a bar 60 mounted 10 on the body of the car 5 and leading to the forward corners of the car and detachably hooked in engagement therewith as at 49. It will thus be seen that either the pawls 33 or the pawl 36 may be released to an inoperative position by manipulating or pulling 15 upon the proper cable 42 or 43 respectively.

On the front of the car body 5 there is pivoted intermediate its ends as at 50 a lever 51 having a detent 52 engageable with the 20 notched quadrant 53. Chains 55 are engaged with the lever 51 one to each side of the pivot 50 and engage with the two arms 15 at their upper ends so that the brakes may be applied by manipulating the lever 25 51 when desired.

The cables 42 and 43 have their ends and the ends of their respective branches released, when it is desired to have the pawls controlled thereby active. If a train of the 30 cars is descending down a hill, pawls 33 will be raised by hooking the end of the cable 42 as at 46 or the end of its branch 47, as at 49, and the pawl 36 is raised to a released position by hooking the end of the cable 35 43 and the end of its branch 48 in the same manner. Thus, as the cars tend to crowd one another, the bumper will be actuated rearwardly so that the shank 25 moves in the casing 24, to actuate the brakes. If a 40 car is allowed to coast until it bumps into another stationary car, the cable 43 and its branch 48 would be unhooked as at 46 and 49 respectively, so that when the shank of the bumper is moved inwardly to set the 45 brakes, said brakes will be maintained in the set position. When backing up a train of cars, the pawls 33 are allowed to engage in the notches 35, by releasing the ends of the cable 42 and its branch 47, thereby preventing 50 the actuation of the brake mechanism because the bumper shank cannot move inwardly of the casing 24.

It is thought that the construction, operation, utility, and advantages of this invention will now be clearly understood without a more detailed description thereof. It will be seen that the structure is exceedingly simple, and compact and convenient in its arrangement so that it is capable of easy 60 and ready manipulation and control.

The present embodiment of the invention has been disclosed in detail merely by way of example since in actual practice it attains the features of advantage enumerated as desirable in the statement of the invention and

the above description. It will be apparent that changes in the details of construction and the combination and arrangement of parts may be resorted to without departing from the scope of the invention as hereinafter claimed or sacrificing any of its advantages.

Having thus described my invention, what I claim as new is:

1. In combination, a car body, wheels supporting the body, a plurality of brake shoes for the wheels, means for actuating and supporting the brake shoes so that they may be applied simultaneously, said means being actuatable by a pair of arms, a casing 75 on the body, a bumper having a shank slideable in the casing, means on the shank engageable with the arms so that when the shank is moved in one direction said arms are actuated to operate the actuating brake 80 means, spring means for normally holding the shank extending outwardly of the casing; a pawl, means for pivotally mounting the pawl, said shank provided with a notch 85 with which the pawl is engageable to hold the shank outwardly and prevent the inward movement thereof; a cable attached to the pawl for releasing the same, a second pawl pivoted on the casing, said shank having ratchet teeth, said pawl last mentioned 90 having a hooked end engageable with said ratchet teeth to prevent the outward movement of the shank by the spring after having been pushed inwardly, a cable for releasing the second pawl, said cables being 95 trained through the bottom of the body and having detachable hook means engageable with the corners thereof.

2. In combination, a car body, wheels supporting the body, a plurality of brake shoes 105 for the wheels, means for actuating and supporting the brake shoes so that they may be applied simultaneously, said means being actuatable by a pair of arms, a casing on the body, a bumper having a shank slideable 110 in the casing, means on the shank engageable with the arms so that when the shank is moved in one direction said arms are actuated to operate the actuating brake means, spring means for normally holding the shank extending outwardly of the casing; a pawl, means for pivotally mounting the pawl, said shank provided with a notch 115 with which the pawl is engageable to hold the shank outwardly and prevent the inward movement thereof; a cable attached to the pawl for releasing the same, a second pawl pivoted on the casing, said shank having ratchet teeth, said pawl last mentioned 120 having a hooked end engageable with said ratchet teeth to prevent the outward movement of the shank by the spring after having been pushed inwardly, a cable for releasing the second pawl, said cables being 125 trained through the bottom of the body and 130

having detachable hook means engageable with the corners thereof, at the rear of the car, and branches on the cables having detachable means engageable with the forward corners of the car.

3. In combination, a car body, wheels supporting the body, a plurality of brake shoes for the wheels, means for actuating and supporting the brake shoes so that they may be applied simultaneously, said means being actuatable by a pair of arms, a casing on the body, a bumper having a shank slideable in the casing, means on the shank engageable with the arms so that when the shank is moved in one direction said arms are actuated to operate the actuating brake means, spring means for normally holding the shank extending outwardly of the casing, a pawl, means for pivotally mounting the pawl, said shank provided with a notch with which the pawl is engageable to hold the

shank outwardly and prevent the inward movement thereof, a cable attached to the pawl for releasing the same, a second pawl pivoted on the casing, said shank having 25 ratchet teeth, said pawl last mentioned having a hooked end engageable with said ratchet teeth to prevent the outward movement of the shank by the spring after having been pushed inwardly, a cable for releasing the second pawl, said cables being trained through the bottom of the body and having detachable hook means engageable with the corners thereof, at the rear of the car, and branches on the cables having 30 detachable means engageable with the forward corners of the car, and manual means for operating said brakes.

In testimony whereof I affix my signature.

EDDIE N. GOINS.
